UNITED STATES PATENT OFFICE.

SAMUEL KANER, OF TORONTO, ONTARIO, CANADA.

CAP.

Application filed August 3, 1925. Serial No. 47,837.

To all whom it may concern:

Be it known that I, SAMUEL KANER, a subject of the Republic of Russia, resident of the city of Toronto, in the Province of Ontario, in the Dominion of Canada, have invented new and useful Improvements in Caps, of which the following is a specification.

The invention relates to improvements in adjustable caps as described in the present specification and shown in the accompanying drawings, which form part of the same.

The invention appertains to the type of adjustable cap in which one or more marginal slits are provided in the crown so that the two edges formed by the slit may be drawn towards one another in varying degrees of proximity in order to regulate the cap and accommodate it for snugly fitting heads of varying sizes.

Whereas caps having such slits are common to the art, the means of adjustment mainly comprise straps or tongues which may be adjusted by fastening means such as dome fasteners, vide Patent Number 1,517,637 for improvements in "caps" granted to me December 2nd, 1924.

The primary object of this invention is to adjustably secure the adjacent edges of the slit without in any way causing them, or portions of the cap thereabout, to pucker or produce bagginess in the surrounding material, such as would deteriorate the general appearance of the cap, and create overlapping of the slit's edges when the same are held tightly together by means of straps or tongues. Such overlapping of the divided pieces of the crown are in practice found to make the cap uncomfortable to the wearer and to be inductive of a headache.

A further object is to form the fastening means into a button of any suitable shape and design and arrange this button so that it entirely conceals the slit, thus greatly enhancing the cap's appearance.

Since it is quite customary in the manufacture of caps to provide an ornamental button on each side of the cap, this invention gives to the button an entirely new and useful purpose. Furthermore, by covering this button with the material of which the cap itself is made, the same may be so construct-

ed as to be practically unnoticeable if so desired.

The invention consists substantially of a slit crown of a cap provided with a button so positioned that it conceals the slit from view, the two edges of the slit being adjustably secured to each other by fastening elements likewise concealed by said button. A very distinctive feature of invention resides in the fastening means, which are devised with a view to guarding against their working loose or becoming inadvertently disengaged.

In the drawings, Figure 1 is a side elevation of a cap showing a button concealing and securing a slit.

Figure 2 is a similar view of the cap showing the button swung back on its hinge in order to expose the slit and also the apertures in its under-face.

Figure 3 is a fragmentary view of the under-side of cap depicting an extension of the sweat-band projecting on the under-side of the slit.

Figure 4 is an enlarged detail of a button securing together the two edges of a slit through a hinge and stud.

Figure 5 is a view of the under-side of the button or fastening means on a similar scale to that of the preceding figure.

Figure 6 is a fragmentary perspective view of the button on a much larger scale illustrating one of its apertures engaged by a hook or fastening stud.

Figure 7 is a similar view exhibiting the manner in which the hook is inserted in the aperture.

Figure 8 is a similar view to Figure 4 and illustrates a slightly modified form of fastening means to the hinge and stud for adjustably connecting the button to the edges of the slit.

Figure 9 is a sectional view, taken on the line 9—9, of the button shown in Figure 8, with its attaching fasteners removed.

Like numerals of reference indicate corresponding parts in each figure throughout the drawings.

Referring to the drawings, the reference numeral 1 indicates the vizor of the cap and 2 its crown, which has a marginal slit 3, preferably V-shaped as shown in Figure 2 and

located at the rear of the vizor. The numerals 4 and 5 indicate the edges of the slit. 6 indicates a button, a rigid wall 7 forming its under-face. This button is of a size sufficient to completely conceal the said slit when positioned thereover.

Let it be remarked at this point that the term "button" is not necessarily confined to the commercialized interpretation of what 10 a button comprises, but is intended to embrace any type of member having a rigid under-face, no matter what shape or design it may form.

This button is hinged at one side to the 15 edge 4 of the slit 3, preferably by means of a metallic tab 8, best discernible in Figures 4 and 5. Said tab is provided with a series of longitudinal apertures 9 by which it is sewn, or otherwise connected, to the fabric 20 of the crown; preferably by embedding it in the wall thereof.

While it is preferable to employ in this connection a metallic tab, it is quite manifest that this button could be attached by 25 means of a flexible strip of cloth or in many other ways common in the art or naturally convenient and suitable, and hence it is not in any way intended to restrict this mode of attachment to any individual form.

30 10 are a series of apertures arranged in staggered relationship on the under-face of the button, which apertures are preferably of a rectangular form and are slightly elongated in a direction transversely of the hinged edge of the slit.

11 is an opposing stud or hook affixed by 40 sewings, or otherwise, to the edge 5 of the slit, such stud comprising a head 12 transversely flattened and a neck 13. This head is of a width slightly less than the length of one of the apertures 10 and greater than its width so that it can only be inserted in a certain manner; namely, by twisting sideways until the head lies parallel with the 45 length of the aperture as depicted in Figure 7, when it is inserted therein and reverted to its regular position again as seen in Figure 6, thus locking it within its aperture and preventing accidental disengagement.

50 By selective engagement of the various apertures it will be readily seen that by this construction the two edges of the slit may be drawn towards one another in varying degrees of proximity in order to tighten or 55 loosen the fit of the cap.

Referring directly to Figure 3, the sweatband of the cap is shown extended at an end as at 14 to overlap the slit in the crown in order to cover it interiorly and with a view to preventing any slight discomfort arising from its edges bearing upon the head of the wearer. Manifestly this would be taken care of in other ways than that shown, such as providing a separate tongue piece; however whilst contributory to the

invention, such does not in itself constitute a determining feature, and the scope of the invention will obviously permit of varying this form of sweat-band extension.

The modified form of the invention depicted in Figures 8 and 9 consists in replacing the hinge 8 and stud 11 with snap fasteners. In this case, a series of receiving apertures 15 are provided in the rigid wall 7 of the button 6, and on opposing sides of 75 said apertures cooperating springs 16 are positioned so as to snap on fasteners inserted in the apertures. It will be readily understood that any design of springs may be employed for this purpose, hence it is 80 not intended to restrict the invention to the particular form illustrated.

Attached to each of the edges 4 and 5 of the slit 3 is a snap fastener, as at 17, commonly termed a "dome fastener", the head 18 of each of these fasteners is of a slightly lesser diameter than the apertures 15 so as to enter therein, where they are gripped at their neck portions by the springs 16.

By this construction then it will be seen 90 that to secure the button to the edges of the slit it is merely necessary to snap the fastener 17 in any two apertures, 15, and by selective engagement of the apertures the proximity of said edges of the slit may be 95 varied in order to regulate the fit of the cap.

Instead of employing the usual dome fastener that rises perpendicularly from its base, it is proposed to make a dome fastener 100 that inclines to one side, as seen in Figure 8, and to so position the fasteners on opposing edges of the slit that they slant away from each other. By so doing, it is ascertained 105 that there is little or no tendency for the fasteners to become inadvertently disengaged.

Whereas in illustrating this cap, a slit is 110 shown on one side thereof as conventional, in close proximity to the edge of the peak, it is, of course, understood that any number of such slits may be employed at any desired point; furthermore, while the mode of connection of the button is set forth as being accomplished by means of studs or 115 snap fasteners, it is clearly evident that hooks and eyes, and other equivalent modes of connection could be similarly used for this purpose without in any way departing from the spirit and scope of the invention; however the manner described in detail herein is preferred by reason of the fact that it provides a more secure locking engagement. It will be observed, also, that whereas this mode of connecting edges of 120 a slit as shown as applied to a cap, may be used in other articles requiring similar adjustment.

What I claim is:

A fastening device for caps or apparel 130

for securing opposing edges of a slit one to the other, comprising a rigid plate, a plurality of apertures therein, a snap fastener for selective engagement in any one of said apertures and for attachment to one edge of aforesaid slit, the head of said snap fastener being inclined to one side of its base so that it may be positioned to slant away

from the direction of pull on the same, spring means carried by said plate for gripping the neck of said snap fastener, and means for connecting the rigid plate to the other edge of the slit. ¹⁰

Signed at Toronto, Ontario, this 30th day of July, 1925.

SAMUEL KANER.
